UNITED STATES PATENT OFFICE.

EDWARD JOHN TIEDE, OF CLEVELAND, OHIO.

PACKING DEVICE FOR FRAGILE ARTICLES.

1,282,656.

Specification of Letters Patent.

Patented Oct. 22, 1918.

Application filed May 14, 1918. Serial No. 284,653.

To all whom it may concern:

Be it known that I, EDWARD J. TIEDE, a citizen of the United States, and a resident of Cleveland, in the county of Cuyahoga and State of Ohio, have invented a new and Improved Packing Device for Fragile Articles, of which the following is a description.

My invention relates to shipping devices and more particularly to a packing device to be formed from stiff paper or pasteboard and adapted for shipping eggs, incandescent lamp bulbs, and like fragile articles.

The prime object of my invention is to provide a packing device comprising a tubular body and separate transverse partitions adapted to be slipped into place in the body and retained in position by tongues on the tubular body, the whole being so formed and arranged that many advantages result, among which are the following: The complete article can be produced from paper or pasteboard without waste of material; the partitions when slipped into place and held by the tongues accommodate themselves to minor irregularities in the contour of the contained article, and resiliently retain the latter in position; the tongues are so formed and positioned relatively to the plane of the partitions that when the tongues are bent into retaining position they are prevented from accidental disengagement from the partitions, so that the latter will be securely held in place; the units or individual packing devices lend themselves to the carrying of articles in large crates or in small lots of any desired number, and the device is useful during all the different stages of wholesale and retail handling up to the final purchaser or consumer. Also, the packing device is light in weight, neat in appearance, presents no exterior projections, and the body, as well as the partitions, may be packed in flat form to occupy the minimum space and may be readily assembled for use.

Reference is to be had to the accompanying drawings forming a part of this specification, it being understood that the drawings are merely illustrative of one example of the invention.

Figure 1 is a longitudinal vertical section of a packing device constituting a practical embodiment of my invention, showing the same in use;

Fig. 2 is an end view thereof;

Figs. 3, 4 and 5 are separate perspective views respectively, of a partition to engage one end of the article, the tubular body, and the second partition;

Fig. 6 is a plan view of the strip from which the tubular body is formed;

Fig. 7 is a plan view of one of the partitions in flat form and before the edge flanges are bent from the plane of the partition.

In producing a practical device in accordance with my invention, a tubular body 10 is provided, preferably rectangular, the same being formed from an oblong strip 10^a as indicated in Fig. 6, which strip is scored to divide the same into five equal panels, of which the end panels 11 are caused to overlap as clearly shown in Figs. 1, 2 and 4, and the overlapped sides are fastened by wire fasteners 12. Two opposite sides 13 of the body 10 are formed with integral tongues 14 of triangular form for retaining the separate transverse partitions 15. The tongues 14 are produced by slitting the material of the body on convergent lines at an acute angle, so that the tongue is integral with the body along a hinge line 16 which is scored. The position of each tongue 14 is such that the angle 17 of the openings or point of convergence of the cuts in the material is inward from the plane of the respective partitions as best seen in Fig. 1. Also, the hinge line 16 or the line on which the tongue joins the body is oblique to the plane of the adjacent partition, whereby when the tongue 14 is bent inwardly over the partition, the point or apex 18 of the tongue will move in an arcuate path transecting the plane of the partition. Thus, with the partitions in place and the tongues bent inwardly over the backs or outer sides of the partitions, the tongues form supports for the partitions, resisting any outward pressure on the latter and at the same time the tongues are prevented from accidentally slipping from engagement with the parts into the planes of the sides of the body on which the tongues are formed. This will be clear from Fig. 1 where it will be seen that the point of a tongue 14, when the partition is in place, cannot resume without force a position with the apex 18 in the angle 17 of the opening.

Each partition is formed with edge flanges 19 extending at all sides, the flanges being at the inner faces of the partitions to be parallel or essentially so with the inner surfaces of the tubular body. The partitions,

however, are of a size to be readily slipped into place, reliance being had on the tongues and not on the tight fit of the partitions to hold the latter in place. Each partition has 5 a central opening and resilient retaining members which vary with the article to be held as for example, an egg or a lamp bulb. The illustrated example is designed for the holding of an egg A, Figs. 1 and 2, there being 10 a central, essentially round opening 20 from which cuts 21 radiate, thereby producing series of resilient tongues 22. In practice, the cuts 21 are of ample width to be readily produced by a die and to facilitate 15 the making of the die.

With the elements of the packing device separated as shown by Figs. 3, 4 and 5, it will be obvious that the body may be collapsed to fold flat and the partitions given 20 a flat form with the flanges 19 thereof in the plane of the partition so that the whole will occupy but little space.

I would state in conclusion that while the 25 illustrated example constitutes a practical embodiment of my invention, I do not limit myself strictly to the mechanical details herein illustrated, since manifestly the same can be considerably varied without departure from the spirit of the invention as defined in the appended claims.

Having thus described my invention, I claim as new, and desire to secure by Letters Patent:

1. A device for shipping fragile articles, 30 the same including an open-ended tubular body, separate transverse partitions fitting within said tubular body and spaced to accommodate the article, said partitions being formed with resilient cushioning members 40 for the ends of the contained article and with

edge flanges projecting at the inner faces thereof, and retaining tongues of triangular form stamped from the interior of said tubular body and integral along one edge of the body for the tongues to be flexed inwardly 45 to positions at the backs of the partitions to prevent displacement of the partitions toward the ends of the body, said triangular tongues being joined to the body on lines oblique to the planes of the respective partitions, and so located that the apexes of the tongues when the latter are bent inward move in arcuate paths transecting the planes of the partitions to effect a bearing of said apexes against said partitions and prevent 50 accidental slipping of the tongues laterally out of engagement with the partitions.

2. A shipping device of the class described, including a tubular body, tongues integral with the body, and partitions separate from the body and adapted to be disposed transversely therein, said tongues joining the material of the body on lines oblique to the planes of the partitions and being bendable over the backs of the partitions. 55

3. A shipping device of the class described, including a tubular body, tongues integral with the body, and partitions separate from the body and adapted to be disposed transversely therein, said tongues joining the material of the body on lines oblique to the planes of the partitions and being bendable over the backs of the partitions, 70 said partitions being spaced to accommodate the article to be held, provided with central openings and with resilient members disposed around said openings to engage the held article. 75

EDWARD JOHN TIEDE.
